UNITED STATES PATENT OFFICE

HARRY DIXSON, OF PELLA, IOWA, ASSIGNOR TO ROLSCREEN COMPANY, OF PELLA, IOWA

ROLLING-WINDOW-SCREEN CONSTRUCTION

Application filed February 19, 1927. Serial No. 169,557.

The object of my invention is to provide a rolling window screen construction wherein the casing and the tracks for the screen may coact with each other for insuring proper alignment of the screen guides or tracks relative to the casing, the parts being simple and easily installed.

More particularly my invention relates to a casing having a slot opening therein through which a screen or the like may be withdrawn from the casing and a pair of bearing plates formed in the casing and spaced inwardly from the ends of the casing, the ends of the slot opening extending beyond the bearing plates for receiving portions of tracks therein whereby the tracks will be positioned and aligned relative to the casing and particularly the slot opening therein through which the screen passes.

Still another object is to provide a track having a fastening flange and a guide or screen edge receiving portion wherein the track may coact with a portion of a casing whereby the guide or screen edge receiving portion will be aligned and positioned relative to the casing so that when the screen or the like is withdrawn from the casing, the side edges thereof will pass into the guide portion of the track.

With these and other objects in view, my invention consists in the construction, arrangement and combination of the various parts of my rolling window screen construction, whereby the objects contemplated are attained, as hereinafter more fully set forth, pointed out in my claims and illustrated in the accompanying drawings, in which:

Figure 1 is a perspective view of the track illustrating the fastening flange, guide portion and the protruding lip.

Figure 2 is a perspective view of one end of a screen casing or housing with the upper end of the track co-acting therewith.

Figure 3 is a front view of the casing and the upper end of the track.

Figure 4 is a sectional view taken on the line 4-4 of Figure 3 and

Figure 5 is a sectional view taken on the line 5-5 of Figure 2.

In the accompanying drawings I have used

the reference character A to indicate generally a casing or housing and B to indicate generally a track construction adapted to coact with the casing A. The casing A includes a top wall 10, a bottom wall 12, a front wall 14 and a back wall 16.

At the junction between the bottom wall 12 and the front wall 14 I provide a slot opening 18 extending the entire length of the casing. In each end of the casing A and spaced inwardly from the ends thereof, is a bearing plate 20. The bearing plate 20 is formed with outwardly extending side flanges which are adapted to rest against the four walls of the casing A and to be secured thereto by spot welding or other suitable means so that the bearing plates 20 are rigidly held within the casing A.

The material of the bottom and front walls adjacent the slot opening 18 is bent over or doubled upon itself so as to provide a rolled up doubled edge upon each side of the slot 18 as at 22. It will be noted that a bearing plate 20 is in each end of the casing and a shaft or the like 24 has its ends projected through the bearing plates 20.

Between the two bearing plates 20 may be mounted a spring roller of any suitable kind (not shown) upon which may be mounted a screen 26. The side edges of the screen 26 are formed with enlarged spaced clips 28.

A screen 26 is designed to pass out of the casing A through the slot opening 18. It will be noted that the ends of the slot opening 18 project beyond the two bearing plates 20.

The track B includes a fastening flange 30 and a guide portion 32. The guide portion 32 is provided with a slot or slit opening 34 which extends lengthwise of the track for permitting the screen 26 to have its side edge extended therethrough and into the guide portion 32.

The clips 28 which are mounted upon the side edges of the screen 26 are designed to travel and be received in the guide portion 32. It will be noted that when the screen is withdrawn from the casing and pulled through the slot opening 18 that it is desirable to always have the side edge of the screen

and the clips thereon to enter into the guide portion 32 of the guide or track B.

The upper end of the fastening flange 30 projects above the upper end of the guide portion 32 so that a protruding part or lip 36 is formed upon the upper end of the track B. The lip 36 is clearly illustrated in Figure 1 of the drawings.

The lip 36 is adapted to extend into the casing A through the slot opening 18 in that portion of the slot 18 beyond or on the outside of the bearing plate 20. The track B below the upper end thereof, engages and abuts against the underside or bottom of the casing A.

The upper end of the guide portion 32 is arranged so that it is in alignment with the slot opening 18 between the two bearing plates 20 or on the side of the bearing plate opposite from the lip 36.

It will be noted that the upper end of the track B coacts with the slot opening 18 and the bearing plate 20 as clearly illustrated in Figures 2 and 5 of the drawings for positioning the track relative to the casing. The tubular portion 32 of the track is thus always insured of being properly positioned relative to the slot opening 18 and in turn relative to the side edge of the screen 26 as well as the clips 28.

The tracks B are thus at their upper end fixed and positioned relative to the casing A which allows easy installation of the rolling window screen construction. Slots 38 are formed in the fastening flange 30 of the track B for securing the tracks B to the sides of the window casing or the like.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. In a structure of the class described, a casing having a slot opening for permitting a screen within the casing to be drawn therethrough, a track having a guide portion provided with a slit opening extending lengthwise of the track, a lip upon the upper end of said track and extending above said guide portion, said lip extending into the slot opening in the casing, whereby the guide portion of the track is aligned with the slot in said casing.

2. In a structure of the class described, a casing having a slot opening for permitting a screen within the casing to be drawn therethrough, a bearing plate in said casing spaced inwardly from the end thereof, said slot opening having its end extending beyond the bearing plate, a track having a guide portion for receiving the side edge of the screen, a lip on

the upper end of said track and extending above said guide portion and into said casing through the slot opening on the outside of said bearing plate.

3. In a structure of the class described, a casing having a slot opening therein for permitting a screen within the casing to be drawn therethrough, a bearing plate in said casing spaced inwardly from the end thereof, said slot opening having its end extending outside the bearing plate, a track having a guide portion for receiving the side edge of the screen, a lip on the upper end of said track and extending above said guide portion and into said casing through the slot opening on the outside of said bearing plate, said guide portion of the track registering with the slot opening in the casing inside said plate, the coacting lip and slot serving to align said guide portion with the slot in said casing.

4. In a structure of the class described, a casing having a slot opening for permitting a screen within the casing to be drawn therethrough, a bearing plate in said casing spaced inwardly from the end thereof, said slot opening having its end extending beyond the bearing plate, a track having a fastening flange and a guide portion, said guide portion terminating short of the upper end of the fastening flange to afford a protruding lip extending into the slot opening in said casing on the outside of said bearing plate.

5. In a structure of the class described, a casing having a slot opening for permitting a screen within the casing to be drawn therethrough, a track having a fastening flange and a guide portion for the screen edge, said guide portion terminating short of the upper end of the fastening flange, to afford a protruding lip adapted to extend into the slot opening of said casing, a portion of said track below the upper end thereof abutting against the underside of the casing.

Des Moines, Iowa, February 2, 1927.
